UNITED STATES PATENT OFFICE

98,386

DESIGN FOR A BOOT HOOK

John A. Farnum, Worcester, Mass.

Application May 20, 1935, Serial No. 56,925

Term of patent 7 years

To all whom it may concern:

Be it known that I, John A. Farnum, a citizen of the United States, residing at Worcester, in the county of Worcester and State of Massachusetts, have invented a new, original, and ornamental Design for a Boot Hook, of which the following is a specification, reference being had to the accompanying drawing, forming part thereof.

Fig. 1 is a side view of a boot hook;

Fig. 2 is a plan view thereof, and

Fig. 3 is an edge view of a boot hook, showing my new design.

The dominating features of the design reside in the contour of the handle and the effect produced by the manner in which the metal part of the boot hook fits into the handle.

I claim:

The ornamental design for a boot hook as shown and described.

JOHN A. FARNUM.
